UNITED STATES PATENT OFFICE.

DAVID MCKINLEY, OF TOLEDO, OHIO.

END-GATE FOR COAL-CARS.

SPECIFICATION forming part of Letters Patent No. 369,018, dated August 30, 1887.

Application filed May 2, 1887. Serial No. 236,899. (No model.)

To all whom it may concern:

Be it known that I, DAVID MCKINLEY, a citizen of the United States, residing at Toledo, in the county of Lucas and State of Ohio, have 5 invented certain new and useful Improvements in a Coal-Car End-Gate; and I do hereby declare that the following is a full, clear, and exact description of the invention, which will enable others skilled in the art to which it applies 10 to make and use the same, reference being had to the accompanying drawings, and to the letters of reference marked thereon, which form part of this specification.

My invention relates to an improved coal-car end-gate, and has for its object to provide means whereby the movable ends of a car can be folded or laid down in a horizontal position within the car without danger of breaking its pivotal attachment, and also when raised to its vertical position within the car shall be capable of being rigidly attached to the sides of the car by means that shall also serve the purpose of preventing the sides from spreading, or, if spread, can be utilized to bring the 25 sides to their proper position, and at the same time so attach the devices by which this result is attained that they shall be out of the way at all times, whether the end-gate is folded or raised, and when lowered shall be protected 30 from breakage or abrasion from any freight that may be thrown upon the end-gate. I attain these objects by the mechanism illustrated in the drawings, in which—

Figure 1 is an elevation of one end of a car 35 provided with my improved end-gate raised in position for the car to be filled, showing also the tension-rods attached. Fig. 2 is an elevation of the same, showing the end-gate folded and illustrating the action of the flexible attachments serving as hinges when obstruction is met by the gate when in the act of folding. Fig. 3 is a perspective view of the inner side of the end-gate. Figs. 4, 5, and 6 are detail views.

Like letters of reference indicate like parts throughout the several views.

A designates the car; B, the end-gate hinged to the car by flexible attachments E, serving as hinges, attached to the car by hooks F, secured to cleat D and to the end-gate by hooks H, attached at the lower side of the gate.

K designates tension-rods having hooks at

one end, and being screw-threaded at their opposite ends and provided with hand-nuts K.

L is an iron attached to the side of the car 55 by bolts, having an enlarged right-angled portion, M, adapted to rest as a brace against the upper edge of the car. This iron has also a perforation through which tension-rod K is placed.

I are strap-irons attached to the upper side of the end-gate and bent at a right angle to closely fit its upper edge. These straps terminate in hooks i. The hooks F and H, by which the ends of the chain are fastened, are formed 65 with a strap portion, G, perforated for bolts f—one or more, as desired—and end in hooks G', of sufficient length to receive the chain-links and be driven into or entirely through the cleats D and C, respectively.

The flexible attachments employed, which serve as hinges, are shown as chains E, and are so proportioned in their lengths that they can be attached to the car at each side and a short distance from the bottom, and are provided at 75 their lower ends with links of a length corresponding to the thickness of the end-gate, the remaining links being but about one-half this length. The lower ends of these chains are attached by hooks H, bolted to the inner sides 80 of the end-gate, these hooks being preferably directly opposite cleat C. With this construction, when the end-gate is raised to its vertical position in the car, the chains should be of just sufficient length to be taut, as shown in Fig. 1, 85 and when the end-gate is lowered, should there be an obstruction in the way, as shown at N, Fig. 2, the top of the gate is permitted to fall to its position on the floor of the car without injury to these flexible attachments, 90 as is the case with any of the forms of attachment now in use.

With the present mode of securing the upper portion of the end-gate there is no means by which the sides of the car can be prevented 95 from spreading. As a consequence, it is found necessary to employ straining-rods running through the end of the car from one side to the other. These rods are greatly in the way when in place and in danger of being lost 100 when removed. By the use of the tension device the end-gate is firmly held in position and the sides of the car prevented from spreading.

This device is operated as follows: The end-

gate is swung to its vertical position, bringing strap I and hook i within reach of the straining-rods K, the hook of which is placed over hook i and hand-nut K screwed firmly to place, 5 bringing the sides firmly against the ends of the end-gate. When it is desired to load the car with bridge-timber, railroad-iron, telegraph-poles, or any long freight extending beyond the length of the car, the straining-rods are 10 loosened and unhooked from hooks i, the rods dropping to the sides of the car entirely out of the way, as shown in Fig. 2, and the end-gate is folded or laid upon the bottom of the car, the chains and hooks upon the end-gate dropping 15 to a position out of danger of breakage or abrasion from the freight, the upper hook being entirely protected, as shown.

The advantages of my device will be at once apparent when it is considered that in the 20 constructions now in use there is no provision for preventing breakage to the hinges when coal or any obstruction is left upon the car-floor when the end-gate is lowered, and also that it is necessary to employ stakes at the 25 ends of the car—a necessity entirely obviated by my improvement.

My device is cheap in construction, durable 20 in its nature, and can be readily attached to any car now in use for the purposes intended, 30 and without alteration or involving additional expense.

Having described my invention, what I

claim, and desire to secure by Letters Patent, is—

1. In an end-gate for coal-cars, flexible attachments serving as hinges attached to the end-gate and to the sides of the car, as and for the purposes set forth. 35

2. In a coal-car, flexible attachments serving as hinges attached to the sides of the car and to the end-gate, adapted to drop to a position out of contact with the freight when the end-gate is down, as and for the purpose set forth. 40

3. In a coal-car, an end-gate flexibly connected with the side of the car, in combination with straining-rods connected to the end-gate and car, as and for the purpose set forth. 45

4. In a coal-car, an end-gate attached at its lower side to the car by flexible connections and at its upper side by straining rods, as and for the purpose set forth. 50

5. In a coal-car, an end-gate attached to the sides of the car by connections attached to the upper and lower sides of the end-gate and adapted to fold out of the way when the gate is down, substantially as set forth. 55

In testimony that I claim the foregoing as my own I hereby affix my signature in presence of two witnesses.

DAVID MCKINLEY.
